UNITED STATES PATENT OFFICE.

JOHN D. FIRMIN, OF PHILADELPHIA, PENNSYLVANIA.

VARIABLE-SPEED DYNAMIC CONTROL FOR ELECTRIC MOTORS.

1,023,105.

Specification of Letters Patent.

Patented Apr. 9, 1912.

Application filed May 31, 1911. Serial No. 630,512.

To all whom it may concern:

Be it known that I, JOHN D. FIRMIN, a citizen of the United States, residing in the city of Philadelphia, State of Pennsylvania, have invented a certain new and useful Variable-Speed Dynamic Control for Electric Motors, of which the following is a specification.

The invention has been particularly developed for use with hoisting motors such as electric crane motors but it is capable of adaptation to other analogous purposes.

A principal object of the invention is to permit fast lowering speeds with no load or a light load and reduce the speed to a safe rate for heavy loads.

Another object is to make this speed control entirely automatic, the change being effected simply by the presence or absence 20 of the load or its weight.

A desirable form of apparatus in which my invention is embodied and which is the best I have up to the present time devised, comprises the electric machine shown and 25 described in the joint application of myself and Arthur E. Hogrebe, for dynamic control for electric machines, Serial No. 619,183, filed March 28, 1911. To that machine my invention adds a truly automatic dynamic 30 control in which the circuit conditions are varied by the load itself without any care or attention on the part of the operator.

I will now describe an exemplifying form 35 of the invention, sufficiently pointing out in connection with this particular embodiment, its characteristics and advantages.

The advantages of the invention will be fully understood by persons skilled in the art and it will also be understood that it is 40 capable of embodiment in greatly varying forms.

In the drawing: Figure 1 is a diagram of an electric machine embodying the invention showing the circuit fully in diagrammatic form; and Fig. 2 is a condensed operative diagram showing the same machine in straight series connection for hoisting.

The machine comprises armature A, field F, series or main resistance R, variable 50 armature resistance R', fixed armature resistance R². The two armature resistances are arranged in series in a circuit A C shunted around the armature. There may also be a brake B in series with the field.

55 The main resistance R comprises contacts 1, 2, 3, 4 and the variable armature resist-

ance R' usually has a similar number of contacts r', r², r³, r⁴.

L designates the positive line and L' the negative line.

As so far described the machine is substantially the same as that shown and described in the joint application above referred to and the operation for lowering is the same on all the four regular running 65 points. The variable resistance R' is gradually cut in as the main resistance R is cut out. The tendency of the load to accelerate the armature sets up a counter electro-motive force in the closed armature circuit 70 A, C and acceleration is thus prevented or regulated. But to provide a high speed when there is no load on the crane hook and to automatically produce a slower safe speed, suitable to the particular load that 75 may be on the hook, the present invention adds to the foregoing an additional variable resistance R² which may be identified as the field shunt resistance. This is in a circuit FS in parallel relation with the field 80 as shown. The circuit FS also contains a permanent resistance R⁴ proportioned to insure that the field will be sufficiently energized when all of the variable resistance is cut out. The circuit is normally broken 85 and is provided with contacts 11, 12, 13, 14, 15, 16,—as many pairs as desired—to close the FS circuit through different amounts of resistance. Movable contacts or bridge pieces 17, 18, 19, one for each pair of contacts 11, 12, etc., are provided and these are urged to retracted position by springs 90 20. In the diagrammatic representation the stems of the contacts 17, 18, 19 constitute magnet armatures, and magnet coils 17^a, 18^a, 95 19^a are provided for the contacts respectively. An additional contact point 5 is provided adjacent to the main resistance controller handle and when the movable contact is thrown all the way over on to point 5, the line circuit is through the conductor K to the first magnet coil 17^a, then through the other magnet coils 18^a, 19^a in series, to contact 5, through the armature and field and back to the negative line. 100 Part of the current tends to pass to the armature closed circuit AC and through the shunt circuit FS around the field whenever that circuit is closed by one or more of the contacts 17, 18, 19.

105 It will now be evident that the field shunt circuit FS is automatically regulated

by the amount of line current. When running on the fifth point the line current all passes through the switch magnets 17, etc. The armature, in lowering, having been brought up to speed by gradually cutting out resistance R , the armature short circuit AC having at the same time been properly regulated by moving the contact of resistance R' to the point r^1 , the movable contact of resistance R is finally placed on point 5. This is the running point for all loads in lowering. If there is no load on the hook a heavy current is now demanded from the line and the magnet switches 17, 18, 19 are so adjusted that in this condition the heavy current causes them all to close, cutting out all of the variable resistance R^3 and allowing only the fixed resistance R^4 to remain in the shunt circuit FS around the field. A relatively great amount of current is thus shunted around the field, producing a weak field and allowing the motor to rotate rapidly, thus quickly and safely lowering the hook. In this case the armature also takes current from the line since it has to drive down the unloaded hook and overcome frictional resistance, etc.

Supposing now a load is put on the hook, the weight of the load tends to rotate the armature and no current is required from the line for lowering purposes except for excitation of the field. The tendency of the armature to revolve now generates a counter-electro motive force in the armature circuit, which reduces the amount of current taken from the line. The greater the load applied to the hook the greater will be the counter-electro motive force generated and the line current will be correspondingly reduced. As the current is reduced, the effect of the switch magnets is reduced.

The operation in running on the fifth point with different loads will now be specifically explained: With no load on the hook the line current is very heavy and all the contacts 17, 18, 19 are closed by the action of their magnets, cutting out all the variable resistance around the field and allowing most of the current to shunt around the field, which is thus made very weak, permitting safe high speed of the motor for rapidly lowering the unloaded hook. When a very light load is placed on the hook the line current is moderately reduced to such an extent that switches 18 and 19 are closed but switch 17 remains open. A small part of the variable resistance is thus added to the permanent resistance in the field shunt circuit; the field strength is somewhat increased and the lowering speed of the armature is reduced. A heavier load will still further reduce the line current and switches 17 and 18 will remain open, but switch 19 will close. The variable resistance is thus further increased and the field strength is

correspondingly increased causing the motor to run still slower. With the heaviest loads on the hook the current is reduced to such an extent that all the switches 17, 18, 19 remain open, giving an open shunt circuit or a full field strength. At the same time for all loads the automatic controlling effect described in the joint application above mentioned is exercised through the closed armature circuit AC.

For all hoisting speeds the connection is in straight series as shown in Fig. 2. The details of the controller or pole changing mechanism are not a part of this invention and need not be described.

I claim:—

1. An electric machine comprising an armature, a field in series therewith, a variable series resistance, a shunt circuit about the armature, a variable resistance therein, a shunt circuit about the field, and automatic means for varying the strength of the field dependent on the load applied to the armature.

2. In an electric machine, the combination of an armature, a series field, a variable series resistance, a shunt circuit around the armature excluding the field, a variable resistance in said armature shunt circuit, a shunt circuit about the field, a variable resistance for said field shunt circuit, and means controlled by a circuit in series with the armature and field for varying said field resistance and consequently varying the field strength.

3. In an electric machine the combination of an armature, a field, a circuit in shunt relation to the armature, a circuit in shunt relation to the field, a variable resistance in the latter, and automatic electric switches in the line circuit for controlling said variable resistance.

4. In an electric machine the combination of an armature, a field in series with the armature, a closed armature circuit, a circuit in shunt relation to the field, a variable resistance therein, one or more switches to control said resistance, magnet coils corresponding to the switches, and a circuit in series with the line for said switch magnets, whereby different rotative loads applied to the armature cause the field strength to be varied and the lowering speed to be controlled.

5. In an electric machine, the combination of an armature, a field, a main resistance in series with the armature, an armature circuit, a resistance therein, a circuit in shunt relation to the field, a variable resistance therein, and automatic means for varying said resistance.

6. In an electric machine the combination of an armature, a field, a main resistance in series with the armature, an armature circuit, a variable resistance therein, a circuit

in shunt relation to the field, a variable resistance therein, and automatic means for varying said resistance.

7. In an electric machine, the combination of an armature, a field, a variable main resistance in series with the field, an armature circuit, a variable resistance therein, a circuit in shunt relation to the field, a variable resistance therein, switches for varying said

resistance, electric magnets for said switches, 10 circuits for said magnets in series with the armature and line, and a contact for controlling said circuit.

JOHN D. FIRMIN.
